Specification for Design.

Patented Jan. 26, 1915.

Application filed November 3, 1914. Serial No. 870,162. Term of patent 14 years.

To all whom it may concern:

Be it known that I, EDWARD R. SARGENT, a citizen of the United States, residing in the city and county of New Haven and State of Connecticut, have invented a new, original, and ornamental Design for Casket-Trimming, of which the following is a specification when taken in connection with the accompanying drawing.

In the drawing, Figure 1 is a face view of

casket trimming embodying my design; Fig. 2 is a section on line 2—2 of Fig. 1; and Fig. 3 is a section on line 3—3 of Fig. 1.

What I claim is:—

The ornamental design for casket trimming, substantially as shown.

EDWARD R. SARGENT.
